UNITED STATES PATENT OFFICE.

SAMUEL P. GEHRET, OF YORK, PENNSYLVANIA.

LATCH.

1,415,871.

Specification of Letters Patent. Patented May 16, 1922.

Application filed October 4, 1920. Serial No. 414,642.

To all whom it may concern:

Be it known that I, SAMUEL P. GEHRET, a citizen of the United States, residing at York, in the county of York and State of Pennsylvania, have invented certain new and useful Improvements in Latches; and I do declare the following to be a full, clear, and exact description of the invention, such as will enable others skilled in the art to 10 which it appertains, to make and use the same.

This invention relates to an improved latch which is especially, although not necessarily, designed for use on automobile doors, the primary object of the invention being to provide a neat, practical latch for automobile doors which is such that it overcomes the necessity of cutting away or mortising the door in order to attach it, which 20 method is very objectionable since it weakens the door, and is very expensive because it necessitates the use of a heavy door in cases where the latter must be mortised for application of the latch.

Another and important object of the invention is to provide a latch which is such that it is adapted for use on either doors which open to the left or to the right, regardless of whether they open forwardly or 30 rearwardly, this being permitted because of the fact that the operating lever is interchangeable.

A further object of the invention is to generally improve upon devices of this class by 35 producing one of extreme simplicity and durability, which consists of comparatively few parts which are so constructed and arranged that rattling is prevented and effectiveness of operation insured.

Other objects and advantages of the invention will be apparent during the course 40 of the following description.

In the accompanying drawings forming a part of this specification, in which like numerals are employed to designate like parts 45 throughout the same:

Figure 1 is a perspective view of a portion of an automobile door showing my improved latch in position thereon.

Figure 2 is a sectional view taken on the plane of the line 2—2 of Fig. 1, looking in the direction of the arrow.

Figure 3 is a perspective view of a latch constructed in accordance with my invention, the cover member being removed to disclose more clearly the latch mechanism.

Figure 4 is a detail perspective view of said cover member.

Referring to the drawings, wherein the preferred embodiment of my invention is 60 clearly disclosed, it will be seen that the numeral 1 designates, as a whole, a casing which is adapted to be placed against one side of a door and secured in position. This casing in its preferred form includes a base 65 plate 2 and a recessed cover plate or member 3 which is fitted against the base plate to form a novel casing for the latch mechanism to be hereinafter described. It is to be noted that the cover member 3 has its 70 rear wall and side walls spaced from the corresponding edges of the base plate, and the uncovered portions of the latter constitute attaching flanges 4, these being apertured for the passage of suitable fastenings there- 75 through. At this point, I wish to state that the cover member may be secured to the base plate in any suitable way. In the showing however, the base plate is provided with slots 5 and the cover member is provided 80 with integral tongues 6 which extend through and are secured in these slots. Attention is directed to the fact that the front wall of the member 3 is slotted, and this front wall, when in position, extends lat- 85 erally beyond the base plate and this ex- tended portion constitutes an additional at- taching flange 7, this flange being also aper- tured for passage of suitable fastenings 90 therethrough. Emphasis is to be laid on this casing construction since the provision of the additional attaching flange 7 greatly assists in properly retaining the casing in 95 position on the door. While on this casing structure, I may mention that the base plate 2 is provided at its forward edge with an extension or tongue 8 which extends through the slot in said front wall, this extension being substantially the same width as the slot 100 and greatly assisting in retaining the cover member and base plate together.

The latch mechanism within the casing includes a slideable locking bolt which is provided at its outer end with a beveled head 9 projectable through the slot in the 105 front wall of the casing, and at its inner end, with an abutment 10 bearing against said base plate and a pair of oppositely dis- posed laterally extending arms 11 which are offset with respect to the longitudinal cen- 110 ter of the bolt in order to space them from the base plate. The combined length of the

two arms 11 is such that their ends extend into close proximity to the opposed side walls of the cover member 3, this proportioning of parts insuring against excessive rattling 5 of the locking bolt and serving to retain it in proper position at all times. The arms 11 are provided with flat faced lateral projections or contact points 12 which bear slidably against the inner face of the cover 10 3. The intermediate portion of the locking bolt is spaced from the base plate and an operating lever 13 is fulcrumed on the base plate and extends transversely across the latter through the space between the locking bolt and said base plate, it being adapted to be brought against the abutment 10 for the purpose of withdrawing the locking bolt to permit the door to be opened. In order to automatically project the locking bolt and 15 retain it in position for operation, I make use of a pair of coiled springs 14, these springs being preferably provided at their opposite ends with attaching eyes and the eyes at one of the ends being connected to 20 the ends of said arms 11 while the eyes at the opposite ends are arranged in seats formed in the laterally extending tongues 15 with which the base plate is provided. I wish to mention at this point that the fulcrum pin which serves to connect the operating handle or lever 13 to the base plate is such that it permits the lever to be detached and reversed as shown in dotted lines 25 in Fig. 1, so that my device to be effectively used on doors which open to the left or to the right and at the same time permit the operating handle to extend above the upper edge of the door for convenient operation.

Emphasis is to be laid on the particular 40 construction of the locking bolt because of the fact that it is provided with portions which contact the inner surfaces of the base plate and cover in such a way as to insure that the head 9 will always be in effective 45 position for projection through the slot through which it slides. Furthermore, this particular construction of locking bolt insures against rattling. Then again, the inclined coiled springs when associated with 50 this particular construction of locking bolt have a tendency to cause the points 12 to bear against the inner surface of the cover plate 3. It follows also that the abutment 10 is caused to bear against the base plate. 55 Hence, it will be seen that this construction is extremely desirable and substantial and that it insures effectiveness of operation and overcomes rattling.

I again wish to emphasize the fact that 60 the particular construction of the casing which I employ enables me to apply my latch on one side of a door and obviate the necessity of cutting and mortising the door as is ordinarily done with most similar devices with which I am familiar. Further-

more, the manner in which I connect the operating handle with the base plate casing enables me to reverse the position of the operating handle to permit the device to be effectively used on either doors which open 70 to the right or to the left. These and other advantages and features of my device have, no doubt, become apparent from the foregoing description.

While I have shown and described my 75 improved latch for use on automobile doors, I wish it to be understood that it is not to be restricted to this particular purpose, since it may be effectively used on many other constructions of closures.

80 A careful consideration of the foregoing description taken in connection with the accompanying drawings, will enable persons skilled in the art to which this invention relates, to obtain a clear understanding of 85 its operation and application of my improved latch. In view of this, a more lengthy description is deemed unnecessary.

Advantageous and effective results are insured with the foregoing construction and 90 arrangement, and for this reason, this construction and arrangement is taken as the preferred embodiment of my invention. However, I wish it to be understood that various minor changes in the shape, size, 95 and arrangement of parts may be resorted to without departing from the spirit of the invention or the scope of the subjoined claims.

I claim:

1. A device of the class described comprising a mechanism casing including a base plate for disposition against one side of the door, and a recessed cover plate connected to the base plate, said cover plate being provided with a relatively wide slotted front wall extending laterally beyond said base plate, this front wall providing an attaching flange and being designed to be disposed against the front vertical edge of the door 100 so as to serve the additional function of a wear plate, and a locking mechanism disposed in said casing, including a bolt projectable through the slot in said attaching flange.

105 2. In a device of the class described, a casing including a base plate for disposition against one side of a door and a recessed cover member resting against the base plate, having its side walls spaced from the edges 110 of the latter, whereby the uncovered parts of said base plate constitute attaching flanges, said cover member being provided with a relatively wide slotted front wall extending laterally beyond said base plate, 115 this front wall providing an additional attaching flange and being adapted for disposition against the forward vertical edge of the door and being apertured for passage of fastenings, and latch means in the casing 120

including a bolt projectable through the slot in said front wall.

3. In a device of the class described, a casing composed of an apertured base plate and a recessed cover plate, the front wall of which is slotted, extended laterally beyond said base and apertured, thus forming an attaching flange, said base plate being provided on its forward edge with an extension 10 passing through the aforesaid slot, said extension being of a width to approximately the same as the slot; and latch mechanism in the casing including a bolt also projecting through said slot.
- 15 4. In a latch, a casing, a slidable bolt provided at its outer end with a head projecting through a slot in the casing, at its inner end with oppositely extending laterally disposed arms, and intermediate its ends with 20 an abutment, coiled springs anchored at one of their ends to the casing and connected at their opposite ends to said arms, and an operating lever fulcrumed in the casing, passing beneath the bolt and engaging said abut-
25 ment.

5. The structure set forth in claim 4, said

arms being offset from the longitudinal center of the bolt to space them from the inner face of the base of the casing and carrying flat contact points bearing against the inner 30 surface of the casing cover.

6. A latch comprising a base plate having lateral tongues at one of its ends, said tongues including seats, a slidable bolt provided at its outer end with a head, and at 35 its inner end with an abutment resting against the base plate and oppositely disposed laterally extending offset arms spaced from the plate and carrying flat faced lugs, coiled springs having eyes at their ends connected to the ends of said arms and arranged in the aforesaid seats, serving to normally project the aforementioned head beyond the plate, an operating lever pivoted on said plate, extending transversely across 40 the same beneath the bolt and engaging said abutment, and a cup-shaped slotted cover, said lugs bearing slidably against the inner face of this cover.

In testimony whereof I have hereunto set 50 my hand.

SAMUEL P. GEHRET.
